PERMANENT CLOTHESPIN

Hijinio J. Andrade, Madera, Calif.

Application January 12, 1951, Serial No. 205,699

5 Claims. (Cl. 24—139)

1

This invention relates to clothespins, and more particularly to clothespins of spring wire material which may be permanently connected to a clothesline.

A main object of the invention is to provide a novel and improved permanent clothespin which is simple in construction, which is very durable, and which is easy to fabricate.

A further object of the invention is to provide an improved permanent metal clothespin which is inexpensive to manufacture, which may be permanently attached to a clothesline, which is provided with multiple elements so that a plurality of articles of clothing may be engaged thereby and held on the clothesline, and which securely clamps clothing without injury to the clothing.

Further objects and advantages of the invention will become apparent from the following description and claims, and from the accompanying drawings, wherein:

Figure 1 is a side elevational view of a portion of a clothesline provided with an improved clothespin arrangement constructed in accordance with the present invention;

Figure 2 is an enlarged top view of an improved clothespin assembly as employed in Figure 1;

Figure 3 is an enlarged, cross-sectional, detail view taken on line 3—3 of Figure 1;

Figure 4 is an enlarged elevational view showing the main member of the clothespin assembly and the auxiliary member thereof just prior to the securing of the auxiliary member to the attaching eye of the main member.

Referring to the drawings, the clothespin assembly may comprise a main clothespin member, indicated generally at 11, and an auxiliary clothespin member indicated generally at 12, which is movably secured to the main member 11, as will be subsequently described. The main member 11 is formed of a single piece of resilient wire bent at its mid-portion to define a large loop having the bight portion 13 and arms 14. The main loop is then again bent at the intermediate portions of the arms 14 to define clamping loops 15, 15, as shown in Figures 1, 2 and 3. The arms 14 are then looped around the bight portion 13 to define holding eyes 16, thereby securing the clamping loops 15, 15 in closed condition. Figure 4 clearly illustrates the configuration of the securing eyes 16. As shown in Figure 2, the remaining portions of the arms of the above-mentioned single piece of wire emerge in side-by-side relation between the holding loops 16, 16 after being bent around the bight 13. Said remaining portions are twisted together in the man-

ner shown at 17, the wire sections being helically twisted around each other to secure them together. At an intermediate portion of the twisted sections, one of the sections is spaced apart from the other to define a fastening eye 18 for the attachment of an auxiliary clothespin element 12. The ends of the wire sections are formed to define a terminal loop 19, said ends being secured together in any suitable manner, as by soldering, at 20.

The auxiliary clothespin element 12 is formed in the same manner as the main element 11, except that the twisted wire end sections are continuous and are not provided with the attaching loop 18. As shown in Figure 4, the wire ends are brought adjacent the loop 18 of a main element 11 and are then bent to define a closed loop 19', shown in dash lines in Figure 4, engaging in the loop 18 of the main clothespin element 11, the wire ends being suitably fastened together, as by soldering, as in the case of the terminal loop 19 of the main clothespin element 11. As shown in Figure 3, the clamping loops 15 may be formed with outwardly divergent bight portions 21 and with parallel intermediate portions 21, 21 of substantial length, providing clamping surfaces for securing articles of clothing, such as the article shown at 22 in Figure 1.

In use, the clothesline, shown at 23, is passed through the terminal loop 19 of the main clothespin element 11, allowing the clamping loops 15, 15 of the respective clothespin elements 11 and 12 to straddle the clothesline, in the manner shown in Figures 1 and 3. The clothesline 23 is freely received inside the terminal loop 19, whereby the clothespin assembly may be moved to any desired position along the clothesline. It will be understood that a number of clothespin assemblies are provided on the clothesline, whereby a plurality of articles of clothing may be hung on the line in side-by-side relationship, the adjacent ends of two successive articles being clamped by the respective clothespin elements 11 and 12 of a single clothespin assembly.

As shown in Figure 4, the terminal portion of the twisted wire sections, indicated at 25, extends at an acute angle with respect to the remaining portion 26 of said twisted sections, the fastening eye 18 being at the junction of the twisted sections 25 and 26. The twisted wire section of the auxiliary clothespin element 12 is substantially equal in length to the portion 26 of the main clothespin element 11. This will be apparent from Figure 4, wherein the twisted section of the auxiliary element, indicated at 26', is approxi-

mately equal in length to the section 26 of the main clothespin element 11. This provides a substantially symmetrical relationship between the clamping loops 15 of the auxiliary clothespin element 12 and the clamping loops 15 of the main clothespin element 11, the auxiliary clothespin element 12, however, being freely rotatable with respect to the main element 11 due to the pivotal connection of the loop 19 with the fastening loop 18.

While a specific embodiment of an improved clothespin assembly has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A clothespin assembly comprising a single piece of resilient wire bent at its mid-portion to define a main loop, said main loop being further bent at the intermediate portions of its arms to define two opposed clamping loops, holding loops at the ends of said main loop, said holding loops extending around the bight portion of said main loop to secure said clamping loops in closed condition, two remaining sections of the wire being helically twisted together, and a terminal loop formed by joining the ends of the wire, said terminal loop being arranged to receive a clothesline.

2. A clothespin assembly comprising a single piece of resilient wire bent at its mid-portion to define a main loop, said main loop being further bent at the intermediate portions of its arms to define two opposed clamping loops, holding loops at the ends of said main loop, said holding loops extending around the bight portion of said main loop to secure said clamping loops in closed condition, two remaining sections of the wire being helically twisted together, a terminal loop formed by joining the ends of the wire, and a loop eye between the helically twisted wire sections, said loop eye being defined by locally separating the wire between the helically wound sections, said terminal loop being arranged to receive a clothesline.

3. A clothespin assembly comprising a single piece of resilient wire bent at its mid-portion to define a main loop, said main loop being further bent at the intermediate portions of its arms to define two opposed clamping loops, holding loops at the ends of said main loop, said holding loops extending around the bight portion of said main loop in side-by-side relation to secure said clamp-

ing loops in closed condition, two remaining sections of the wire being helically twisted together, the twisted remaining sections being bent to an acute angle at their intermediate portion, a terminal loop formed by joining the ends of the wire, a loop eye between the helically twisted wire sections, said loop eye being defined by locally separating the wire between the helically wound sections, and a further wire clothespin engaged with said loop eye, said further clothespin being formed from another continuous piece of resilient wire and having two opposed clamping loops, said terminal loop being arranged to engage a clothesline between the respective pairs of clamping loops.

4. A clothespin assembly comprising a single piece of resilient wire bent at its mid-portion to define a main loop, said main loop being further bent at the intermediate portions of its arms to define two opposed clamping loops, holding loops at the ends of said main loop, said holding loops extending around the bight portion of said main loop to secure said clamping loop in closed condition, two remaining sections of the wire being helically twisted together, the twisted remaining sections being bent to define an acute angle at their junction, and a terminal loop formed by joining the ends of the wire, said terminal loop being arranged to receive a clothesline.

5. A clothespin assembly comprising a single piece of resilient wire bent at its mid-portion to define a main loop, said main loop being further bent at the intermediate portions of its arms to define two opposed clamping loops, holding loops at the ends of said main loop, said holding loops extending around the bight portion of said main loop to secure said clamping loop in closed condition, two remaining sections of the wire being helically twisted together, the twisted remaining sections being bent to define an acute angle at their junction, a terminal loop formed by joining the ends of the wire, and a loop eye at the bend at said intermediate portion of the helically twisted wire sections, said loop eye being defined by locally separating one of said remaining sections of wire from the other, said terminal loop being arranged to receive a clothesline.
